DESIGN FOR A HAT OR SIMILAR ARTICLE

Rose Jacobson, New York, N. Y.

Application July 11, 1941, Serial No. 102,023

Term of patent 3½ years

To all whom it may concern:

Be it known that I, Rose Jacobson, a citizen of the United States of America, residing in New York city, county of Kings, and State of New York, have invented a new, original, and ornamental Design for a Hat or Similar Article, of which the following is a specification, reference being had to the accompanying drawing, forming part thereof, wherein,

I claim:

The ornamental design for a hat or similar article, substantially as shown.

ROSE JACOBSON.
